CLAIM

The ornamental design for a light fixture, as shown and described.

DESCRIPTION

This application is related to commonly assigned Application No. 10/757,623 filed Jan. 14, 2004, now pending, and to commonly assigned, concurrently filed Application No. 29/221,167, Application No. 29/221,163 and Application No. 29/221,162, all still pending, the full disclosures of which are fully incorporated herein by reference.

FIG. 1 is a photograph of an isometric view of a first embodiment of the light fixture of the present invention; FIG. 2 is a photograph in a front elevation view thereof, the side and rear views being identical thereto;

FIG. 3 is a photograph from below thereof;

FIG. 4 is a photograph of a second embodiment;

FIG. 5 is a photograph of a third embodiment;

FIG. 6 is a photograph of a fourth embodiment;

FIG. 7 is a photograph of a fifth embodiment; and,

FIG. 8 is a photograph of a sixth embodiment.
